END BELL HOUSING

Ralph L. Jaeschke, Kenosha, Wis., assignor to Eaton Yale
& Towne Inc., Cleveland, Ohio, a corporation of Ohio

Filed Apr. 30, 1969, Ser. No. 16,952

Term of patent 14 years

Int. Cl. D13—01

U.S. Cl. D26—5

FIG. 1 is a perspective view showing my invention of an end bell housing with typical environment shown in phantom.

FIG. 2 is a side elevational view of the invention.

FIG. 3 is a front elevational view of the invention.

FIG. 4 is a rear elevational view of the invention.

The broken line showing of motor elements is for illustrative purposes only.

I claim:

The ornamental design for an end bell housing, as shown and described.
